UNITED STATES PATENT OFFICE.

DONALD H. McCORKLE, OF BERKELEY, CALIFORNIA.

DESIGN FOR A GAS-HEATER GRILL.

50,790.

Specification for Design. Patented May 15, 1917.

Application filed January 31, 1917. Serial No. 145,801. Term of patent 14 years.

To all whom it may concern:

Be it known that I, DONALD H. McCORKLE, a citizen of the United States, residing at Berkeley, in the county of Alameda and State of California, have invented a new, original, and ornamental Design for a Gas-Heater Grill, of which the following is a specification, reference being had to the accompanying drawing, forming part thereof.

Figure 1 is a front elevation of a gas heater grill, showing my new design.

Fig. 2 is a side elevation of the same.

I claim,

The ornamental design for a gas heater grill, as shown.

In testimony whereof I affix my signature.

DONALD H. McCORKLE.
